(57) **CLAIM**

The ornamental design for a computing device, as shown and described.

DESCRIPTION

FIG. 1 is a perspective view of a computing device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top side elevational view thereof;

FIG. 7 is a bottom side elevational view thereof;

FIG. 8 is another perspective view thereof; and,

FIG. 9 is an exploded view thereof which illustrates the three segments of the computing device (top, middle, and bottom) being separated.

Broken lines shown in the figures illustrate portions of the computing device and form no part of the claimed design.
